(57) **CLAIM**

The ornamental design for a food product steamer, as shown and described.

DESCRIPTION

FIG. 1 is a front perspective view of a food product steamer, showing our new design;

FIG. 2 is a rear perspective view thereof;

FIG. 3 is a top view thereof;

FIG. 4 is a side view thereof;

FIG. 5 is a bottom view thereof;

FIG. 6 is a side view thereof;

FIG. 7 is a front view thereof; and,

FIG. 8 is a rear view thereof.

The broken lines represent unclaimed boundaries of the design. The vertical shading lines are for illustrative purposes only and form no part of the claimed design.
